UNITED STATES PATENT OFFICE.

FRANK HEEBEK, OF CLEVELAND, OHIO.

GUARD FOR WRINGERS AND IRONING MACHINES.

Application filed April 18, 1921. Serial No. 462,099.

To all whom it may concern:

Be it known that I, FRANK HEEBEK, a citizen of the United States, and a resident of Cleveland, county of Cuyahoga, and State 5 of Ohio, have invented a new and useful Improvement in Guards for Wringers and Ironing Machines, of which the following is a specification, the principle of the invention being herein explained and the best 10 mode in which I have contemplated applying that principle, so as to distinguish it from other inventions.

The present invention, relating, as indicated, to a guard for wringers, ironing machines and the like, is particularly directed to the provision of a simple device which may either be constructed as a part of the ironer or wringer, or may be attached thereto for the purpose of facilitating the feeding 20 of the garments between the rolls, and for the further purpose of guarding the operator against being caught between the operating rollers of the machine. To the accomplishment of the foregoing and related ends, said invention, then, consists of the means hereinafter fully described and particularly pointed out in the claim.

The annexed drawing and the following description set forth in detail certain mechanism embodying the invention, such disclosed means constituting, however, but one of various mechanical forms in which the principle of the invention may be used.

In said annexed drawing:—

Fig. 1 is a side elevation of my device as 35 applied to a wringer of standard type; Fig. 2 is a longitudinal vertical section through the same; Fig. 3 is a plan view taken below the plane indicated by the line 3—3, Fig. 1; and Fig. 4 is a detail section along the 40 line 4—4, Fig. 2.

In Fig. 1 I have shown, for purpose of illustration, a wringer of standard type which comprises spaced vertical frame members 1, connected, as in the usual manner, by cross- 45 pieces and provided with vertically arranged slots 2, in which are mounted the bearing portions or studs 3 of two co-operative rollers 4 and 5. The roller 4 is maintained in operative relation to the roller 5 by means 50 of heavy coil springs 6, the tension of which may be adjusted by means of hand screws 7 carried in the upper portion of the frame members 1, as is customary in devices of this type.

55 In the operation of a wringer or an iron-

ing machine it is customary to feed the garments by hand, and numerous accidents have occurred by reason of the operator's hands or fingers being drawn in between the co-operative operating rolls of the machine. I understand that it has been proposed to place a lighter and movably mounted guard roller in front of the main co-operative rolls for the protection of the operator's hands, 60 but the present invention goes very much further than merely the use of the guard roller referred to, and provides a double 65 guard against injury, as well as providing means which greatly facilitate the feeding 70 of the garments between the main rolls.

The present invention consists of a pair of plates 8 which may be attached to the side faces of the two wringer frame members 1. To these plates 8 are attached horizontally extending frames 9, to the ends of which are adjustably mounted rolls 10. The adjustment of these rolls may be had in any convenient manner, such, for example, as by means of bolts 11 operating against slide 75 blocks 12. Extending around the two oppositely arranged rollers 10, which are of course parallel to the main rollers 4 and 5, is an endless belt 13, which is also passed between the main rollers 4 and 5, and over 80 a roller 14 carried between the plates 8. All of the rollers referred to are of course in parallel relation.

Mounted on the extending frames 9 are four vertically arranged rods 15, on the upper ends of each pair of which are mounted 85 guard rollers 16. These rods 15 extend a considerable distance below the frames 9 and carry washers or plates 17 at their lower ends, between which and the frame members 95 are mounted compression springs 18. These compression springs serve to maintain the roller 16 in contact with the upper surface of the belt 13 and in the position shown in Figs. 1 and 2.

In operation the garments to be passed between the main rollers 4 and 5 may merely be held upon the inclined surface of the belt 13 on the side which is moving toward the rollers 4 and 5. The belt 13 can conveniently be formed of live rubber, or some similar material and will present a sufficiently frictional surface so that garments laid upon it will be carried up on this belt beneath the guard rollers 16, and then between the rollers 4 and 5. The presence of 100 105 110 this belt 13 makes it unnecessary in most

- cases for the operator to maintain his hands on the garments after they have first been laid upon the belt. In some cases, however, where the garments must be spread out or held in a certain position before they are passed between the main rollers the hands of the operator must necessarily remain on the garment until it is quite close to the main rollers. To insure against carelessness which would cause the hands to be caught in the rollers 4 and 5 the guards 16 are provided, and should a hand be caught between this roller and the belt, the roller will give upwardly because of its resilient mounting, allowing the hand to be pulled away before it is caught by the main rolls. Of course, also, as soon as a hand touches a roller the operator will stop the machine in any event. Not only does the present device provide a means which obviate the necessity for the operator's holding the garment in most cases, but it provides a guard which warns the operator before the hands have been caught between the main rollers. A further advantage is that the present device is so simple in its construction that it may be readily attached to wringers and similar machines which are already in use, and does not require to be built into the machine. It will be understood that while I have described and illustrated my invention as applied to a wringer it may equally well be

applied to an ironing machine or similar apparatus with but very slight modification.

Other modes of applying the principle of my invention may be employed instead of the one explained, change being made as regards the mechanism herein disclosed, provided the means stated by the following claim or the equivalent of such stated means be employed.

I therefore particularly point out and distinctly claim as my invention:—

An attachment for a wringer comprising spaced frame members adapted to be engaged upon the vertical frame members of a wringer, a pair of rollers adjustably supported in the ends of said frame members, respectively, on opposite sides of said wringer, an endless belt mounted about said rollers, said belt being passed between the co-operative rollers of the wringer, a pair of vertically slideable rods mounted on said first-mentioned frame members on each side of and adjacent said wringer rollers, resilient elements on the lower ends of each of said rods, and guard rollers journaled respectively in the upper ends of said rods in parallel relation with the wringer rollers and held in resilient contact with said endless belt.

Signed by me, this 12th day of April, 1921.

FRANK HREBEK.
